UNITED STATES PATENT OFFICE.

GLENN F. BOWLING, OF CHICAGO, ILLINOIS.

RECEPTACLE STAND.

Application filed January 12, 1924. Serial No. 685,913.

To all whom it may concern:

Be it known that I, GLENN F. BOWLING, a citizen of the United States, residing at Chicago, in the county of Cook and State of Illinois, have invented new and useful Improvements in Receptacle Stands, of which the following is a specification.

This invention relates to supports having particular reference to receptacle-stands.

10 A primary object of the invention is the provision of a stand, commonly called a "bucket jack", designed to support a bucket or pail of painting or decorative material on a scaffold, or plank extended between two 15 or more ladders, said support being adapted to keep the bucket or pail of painting or decorative material in an elevated and readily accessible position.

The invention has for a further object the 20 provision of new and improved means whereby the "bucket jack" may be slid longitudinally with respect to the scaffold or plank as the painting proceeds.

25 A further object of the invention resides in the provision of means for keeping the contents of the bucket or pail of painting material in a horizontal position in the event the scaffold or plank is suddenly removed from its horizontal position of rest and assumes an inclined position.

30 A still further object of the invention is to provide an attachment which may be applied to the support to hold smaller sized cans or pails, and maintain the same in a horizontal position.

With these objects in view the invention consists in the novel construction and arrangement of parts, hereinafter described, illustrated in the accompanying drawings, 35 and particularly pointed out in the appended claims, it being understood that various changes in the form, proportions, size and minor details of construction may be made within the scope of the appended claims 40 without departing from the spirit or sacrificing any of the advantages of the invention.

In the accompanying drawings:

Figure 1 is a front elevation of the device, 50 the bucket and scaffold being shown in broken lines; Fig. 2 is a side elevation thereof showing the means for slidably securing said device to either side of a scaffold; Fig. 3 is an enlarged cross-sectional view on 55 the line 3-3 of Fig. 1 to clearly illustrate the position of the various parts co-acting

to render the device readily extensible; Fig. 4 is a horizontal sectional view on the line 4-4 of Fig. 1, illustrating the pivoted ring-support; Fig. 5 is an inverted plan view of Fig. 2 showing the relative positions of the rails and extensible bar; Fig. 6 is an elevation, partly in section of a modified form of carrier used for the purpose of supporting small-sized cans; and Fig. 7 is an enlarged plan view thereof.

Referring now more in detail to the drawings, in which like characters of reference denote similar parts throughout the several views, the numeral 10 denotes generally the framework of my improved support. As shown in the drawings this framework may be constructed entirely of strap iron bent to the desired shape. Said standard comprises essentially two similar parts, 11 and 12, each 75 made from a single piece of strap iron, and when secured together, as indicated at 13, assume the configuration depicted by Fig. 1, having a flared base portion 14 and a receptacle support proper 15. While not absolutely necessary, I prefer to add the braces 16 and 17, their use compensating for the compression stresses caused by loading the support. The tips of the base portion 14 are bent laterally to form feet 18 for attaching 80 the standard to its supporting means.

The supporting means, above referred to, comprises two channel members 19 and 20. To the shorter channel, designated by the numeral 19, is secured the feet 18 of the 90 base portion 14, said channel being adapted to slide over the channel 20. On reference to Fig. 1, it will be noted that said channel 20 is somewhat longer than said channel 19, so the latter may be termed a "channel-rail" 95 on which the device may be slidably adjusted longitudinally of the scaffold. When in their assembled relation said channels 19 and 20, by preference, assume the position indicated in Fig. 3, wherein their respective 100 flanges are oppositely directed, the flanges 19^a having sufficient clearance to slide above and below the scaffold 21. The upper face of said channel 19 is pressed out, as indicated at 23, for the reception of rollers 24, 105 which rest on the upper face of the channel-rail 20 for the purpose of facilitating the sliding movement of the first-named channel.

While said channel-rail 20, in most instances, may prove to be of sufficient length 110 to permit the support to be adjusted along the entire length of the scaffold, cases may

arise in which greater latitude of longitudinal movement of said receptacle-support, might be necessary and highly desirable. To meet such emergencies I provide a medium length bar 25 which is slidably mounted within said channel 20. Thus, when the support has travelled the entire length of the channel-rail 20, and it is desired to further move said support along the scaffold, 10 it is only necessary to slide out said bar 25 and insert its outer end within the looped portion 26 of the bracket 27. The channel 20 and bar 25 now form a continuous rail and the support in most instances will be 15 free to move the entire length of the scaffold.

To compensate lateral stresses to which the device may be subjected, the opposite edge of the scaffold 21 is provided with a channel 20^a, like unto channel 20, and similarly mounted to said scaffold. Within said channel 20^a is slidably mounted a bar 25^a adapted to be withdrawn therefrom to form an extensible rail for insertion in the looped end of the bracket 27^a. Thus, by 20 this construction both edges of the scaffold are provided with rails. The support or "bucket jack" is connected to the channel 20^a by means of an extensible bracket 28, which passes beneath the scaffold, having 25 one end bent at right angles and secured to the framework by means of the filler piece 29, while its other end is formed with a loop 30 (Fig. 2) within which is slidably mounted said channel 20^a. Said bracket 28 30 may be adjusted to accommodate itself to the varying widths of scaffolds, as indicated at 31.

The top of the framework 10, which I have termed as the receptacle support 40 proper 15, is provided with a ring 32, being pivoted thereon by means of diametrically opposite wingbolts 33. Within this ring 32 is inserted the bucket or pail of paint, the beaded portion of the latter resting on the 45 top of the ring and holding said bucket in suspension. The bucket or pail is now in pivoted relation to the support, so in the event the scaffold is moved, and the support departs from its vertical position, such 50 movement of the support will not be imparted to the bucket, the latter by gravity remaining in a vertical position. Thus the danger of spilling the paint is exceedingly remote.

55 The modification depicted in Figs. 6 and 7 has been designed where small cans of paint are to be used. This structure comprises the cylinder 34, formed with upwardly directed flared arms 35, having their 60 tips apertured for the reception of the wingbolts 33. The tips of these arms fit within the ring 21 and hang therefrom in pendant swingable position. The can of paint is inserted within said cylinder or ring 34 and 65 due to its pivotal relation to the framework,

is protected from any spilling of its contents as in the case of the bucket above referred to.

It will now become apparent that my device will keep the paint or decorative material always within reach of the painter as the work progresses obviating the necessity of stooping and bending over, by simply sliding the support along the rail. My invention also gives free use of the scaffold 70 as the support is attached to the side of the same. The scaffold is free of obstruction. The stand is easily removed when not in use by simply sliding it off the end of the 75 channel-rail.

Having thus described my invention, I claim as new and desire to secure by Letters Patent:

1. A bucket support for horizontal scaffolds comprising a standard, a horizontally arranged channeled attaching member supporting the standard, and a rail member extending through the attaching member and supporting the same for movement longitudinally of the scaffold. 80

2. A bucket support for horizontal scaffolds comprising a standard, a horizontally arranged channeled attaching member supporting the standard, a rail member extending through the attaching member and supporting the same for movement longitudinally of the scaffold, and a bar extending through said rail member and having means whereby the same may be secured at spaced points to a horizontally arranged scaffold. 90

3. A bucket support for horizontal scaffolds comprising a standard, a horizontally arranged channeled attaching member supporting the standard, a rail member extending through the attaching member and supporting the same for movement longitudinally of the scaffold, a bar extending through said rail member and having means whereby the same may be secured at spaced points to a horizontally arranged scaffold, 100 and a bracing device connected to the standard and extending across the scaffold. 110

4. The combination with a scaffold, or analogous device, of a vertical receptacle-support comprising a framework embodying a base portion and a receptacle support proper, a horizontal channel carrying said framework, a horizontal channel-rail secured to said scaffold and longitudinally through the first-named channel thereby 120 permitting the same to move longitudinally thereof, and a ring horizontally pivoted to said receptacle support proper.

5. The combination with a scaffold, or analogous device, of a vertical receptacle-support comprising a framework, a horizontal channel carrying said framework, a horizontally arranged channel-rail secured to said scaffold and extending longitudinally through the first-named channel thereby 125 130

permitting the latter to move longitudinally, an extensible bar carried by said channel rail and adapted to be withdrawn therefrom, a bracket secured to said scaffold and 5 having a looped end for the reception of the outer end of said extensible bar and means adapted to maintain a receptacle in a vertical position, said means comprising a ring pivoted to the upper portion of said frame-
10 work.

6. The combination with a scaffold, or analogous device, of a receptacle-support comprising a framework, a channel carrying said framework, a channel-rail secured

to said scaffold and insertible within the 15 first-named channel thereby permitting the latter to move longitudinally, a second channel secured to the opposite edge of said scaffold, an extensible bar secured to said framework and having one end looped to slidably 20 engage said second channel and means adapted to maintain a receptacle in a vertical position, said means comprising a ring pivoted to the top section of said frame-
25 work.

In testimony whereof I affix my signature.

GLENN F. BOWLING.
